UNITED STATES PATENT OFFICE.

JONATHAN J. MOORE AND JAMES A. BALL, OF THORNTOWN, INDIANA, AS-SIGNORS OF ONE-HALF TO J. C. TAYLOR, OF SAME PLACE.

BELT-GUIDE.

SPECIFICATION forming part of Letters Patent No. 320,810, dated June 23, 1885.

Application filed October 11, 1884. (No model.)

To all whom it may concern:

Be it known that we, JONATHAN J. MOORE and JAMES A. BALL, citizens of the United States, residing at Thorntown, in the county 5 of Boone and State of Indiana, have invented a new and useful Improvement in Belt-Guides, of which the following is a specification.

Our invention relates to an improved belt-guide for a round belt when used to convey power from a thrasher to a straw-stacker, or other like situation where the respective pulleys over which the belt passes are not in line with each other.

15 The object of our improvement is to provide such a guide which can be readily adjusted to guide the belt in different situations, or from either side of the thrasher, all as hereinafter described.

20 The accompanying drawings illustrate our invention.

Figure 1 represents a side elevation of our device. Fig. 2 is a front elevation of the same. Fig. 3 is a side elevation showing the 25 application of our device to a belt connecting a thrasher and a straw-stacker.

As is a standard adapted to be bolted or otherwise secured to the under side of the thrasher straw-carrier *b*, as shown in Fig. 3. 30 The lower end of said standard is enlarged to form on one side a broad circular bearing for a bracket, *c*, which is adapted to turn on said standard in a plane parallel with the side of the straw-carrier, said bracket being clamped 35 in position by a bolt, *d*, which also forms the pivot on which the bracket turns.

To the upper end of the face of bracket *c*, at a right angle to the bearing on standard *a*, is secured, so as to be adjustable in a 40 plane parallel with said face of the bracket, an arm, *e*, which is held in place by the pivotal bolt *f*.

To the outer end of arm *e* is secured a short shaft, *g*, also adjustable in the same plane as the arm, and secured thereto by the pivotal bolt *h*. A grooved pulley, *i*, turns freely on shaft *g*.

To the lower end of bracket *c* is adjustably secured by a pivotal bolt, *x*, a shaft, *k*, and 50 a bracket, *l*, said shaft and bracket *l* being formed in one piece so that they maintain the same relative position. A pulley, *j*, turns freely on shaft *k*.

For the purpose of compensating for the expansion and contraction of the rope belt *m*, 55 a binder-pulley, *n*, is mounted in the forked free end of an arm, *o*, which is hinged to the bracket *l*, as shown.

p is a grooved pulley designed to act as a driving-pulley to carry belt *m*, and by the use 60 of our improved belt-guide we avoid the necessity of removing one of the shafts forming part of the thrasher mechanism to fix said pulley on said shaft opposite the guiding-pulleys *s t* on the straw-stack, as has heretofore 65 been the practice, but we secure said pulley to the outer end of said shaft, or to the arms of an outside pulley, *r*.

In operation belt *m* is passed round pulley *p* and over pulleys *i* and *j*, and from thence 70 to the driving-pulley *n* on the stacker, passing under the guide-pulleys *s t*, which are opposite the center of the thrasher straw-carrier, as fully explained in Letters Patent granted to us April 1, 1884, No. 295,932. Bracket *c* is now 75 adjusted and secured so that its face, to which the shafts *g* and *k* are secured, is at substantially a right angle with the line of the belt. Shafts *g* and *k* are now set so that their respective pulleys will turn in planes corresponding to 80 the angles formed by the belt passing from the pulley *r* to pulleys *v* and *w*, so that the belt will run easily over them to the said pulleys. Arm *e* permits the necessary outward adjustment of shaft *g*. Binding-pulley *n* is now 85 caused to rest on the lower or slack side of the belt, and it is ready to run.

We claim as our invention—

1. The belt-guide consisting of the standard *a*, bracket *c*, arm *e*, shafts *g* and *k*, bolts 90 *d*, *f*, *h*, and *x*, and pulleys *i* and *j*, all combined in the manner specified.

2. The combination, with a belt-guide, a binder-pulley, and an arm carrying said pulley, of a bracket formed integral with one of 95 the shafts of said belt-guide, and forming a hinged support for said arm, substantially as and for the purpose specified.

JONATHAN J. MOORE.
JAMES A. BALL.
